UNITED STATES PATENT OFFICE.

FRANK A. COLLIER, OF GALVESTON, TEXAS.

WRENCH.

1,177,488.

Specification of Letters Patent. Patented Mar. 28, 1916.

Application filed March 20, 1915. Serial No. 15,920.

To all whom it may concern:

Be it known that I, FRANK A. COLLIER, a citizen of the United States of America, residing at Galveston, in the county of Galveston and State of Texas, have invented new and useful Improvements in Wrenches, of which the following is a specification.

The present invention relates to improvements in that class of wrenches known as sliding jaw and the primary object of the invention is to produce a wrench of an effective and durable construction, which may be cheaply manufactured and easily and quickly operated.

With the above and other objects in view, the improvement resides in the construction, combination and arrangement of parts set forth in the following specification and falling within the scope of the appended claim.

In the drawing there has been illustrated a simple and satisfactory reduction of the improvement to practice, and in said drawing: Figure 1 is a side elevation of a wrench constructed in accordance with the present invention. Fig. 2 is a sectional view on the line 2—2 of Fig. 1. Fig. 3 is a similar sectional view on the line 3—3 of Fig. 1, looking in the direction of the arrows. Fig. 4 is a section on the line 4—4 of Fig. 1, also looking in the direction of the arrows.

In the accompanying drawing, the numeral 1 designates the outer jaw of the wrench, which is curved upon its opposite faces, its inner or working face being provided with teeth 2. The jaw is provided upon one of its ends with an integrally formed angularly arranged shank 3, which is preferably rectangular in cross section.

The numeral 4 designates the inner jaw, the opposite faces of which being also curved and the outer or working face being provided with teeth 5. The jaw is integrally formed with an angularly extending shank or lever 6, and the said lever has its end, (provided with the jaw 4) formed with a substantially rectangular yoke 7 which receives the shank 3 of the jaw 1, so that the said shank is arranged over one of the faces of the lever 6.

The lever has its inner face or edge

rounded inwardly, the said rounded portion being formed with threads 8, and the opposite sides of the said lever are provided with centrally arranged longitudinally extending grooves 9—9. Arranged to travel upon the lever 6 is a carriage 10, the same having pivotally arranged within a suitable opening, a turning screw 11, the threads of the said screw being milled to facilitate the manipulation of the same, and the said threads engage with the threads 8 of the lever 6. The carriage 10, is, of course, provided with an opening for the reception of the lever 6, and the sides of the said carriage at the opening thereof are formed with lugs or tongues 12 which are received within the grooves 9 of said lever. The opening through which the lever is passed is preferably extended to the upper end 13 of said carriage, and the sides of the carriage, above or opposite the lever 6, are formed with elongated openings 14 which receive trunnions 15 provided upon the opposite sides of the shank, the said shank being passed through the opening in the carriage. Secured to the end of the shank 3 and bearing upon the lever 6 is a flat spring 18 which has a tendency to move the shank to tilt the same to bring the jaw 1 toward the jaw 4.

From the above description, taken in connection with the accompanying drawing, the simplicity of the device as well as the advantages thereof will, it is thought, be perfectly apparent to those skilled in the art to which such invention appertains without further detailed description.

I claim:

A wrench including a stationary jaw having a yoke member integral therewith and an angularly toothed shank having its opposite sides grooved longitudinally, a movable jaw having a shank passing loosely through the yoke of the stationary jaw, a carriage upon the shank of the stationary jaw having lugs received in the grooves thereof and provided with a screw engaging with the teeth of said jaw, said carriage having an opening to receive the end of the shank of the movable jaw, and a shank having lateral trunnions extending through

elongated openings in the sides of said carriage, and a spring secured to the ends of the mentioned shank of the movable jaw and having its end curved and bearing
5 against one of the edges of the shank of the stationary jaw.

In testimony whereof I affix my signature in presence of two witnesses.

FRANK A. COLLIER.
